DELIVERY FOR SIGNATURE STITCHING MACHINES AND THE LIKE

John W. Miller, Benton Harbor, Mich., assignor to F. P. Rosback Company, Benton Harbor, Mich., a corporation of Michigan

Application October 15, 1952, Serial No. 314,884

17 Claims. (Cl. 112—21)

This invention relates, as indicated, to signature stitching machines and the like, and more particularly to a compact and efficient delivery for collecting the stitched assemblies discharged from such machines.

The invention, while not limited thereto, is concerned principally with signature stitching machines of the saddle type, wherein the stitched assemblies are ejected by being displaced beyond the discharge end of the saddle, and has for a primary object the provision of a delivery mechanism adapted to receive the assemblies thus discharged and automatically to transfer them to a convenient collection point from which they may be readily removed for further handling. It is also an object of my invention to provide such a delivery mechanism including a belt conveyor and transfer means operative in timed relation with operation of the stitching machine to deposit the signature assemblies as discharged flatwise upon the conveyor. Another object of my invention is to provide a delivery mechanism including a belt conveyor and transfer means of this nature wherein the conveyor advances in response to operation of the transfer means. It is an additional object of my invention to provide means for adjusting the thus responsive advance of such belt conveyor. Other objects and advantages will become apparent as the following description proceeds.

To the accomplishment of the foregoing and related ends the invention, then, consists of the means herein-after fully described and particularly pointed out in the claims.

The annexed drawings and the following description set forth in detail certain mechanisms embodying the invention, such disclosed means constituting, however, but one of various mechanical forms in which the principle of the invention may be used.

In said annexed drawings:

Fig. 1 is a front elevation of my delivery mechanism shown in operative association with a signature stitching machine of the type with which it is designed to operate;

Fig. 2 is an end elevation of the apparatus shown in Fig. 1 as viewed from the left thereof;

Fig. 3 is a partial end view of the apparatus illustrating parts of the delivery mechanism in a different operative position;

Fig. 4 is a vertical section taken on the plane of the line 4—4 in Fig. 1;

Fig. 5 is a top plan view of the delivery mechanism.

Referring now to the drawings, and especially to Fig. 1, my improved delivery mechanism is there shown in combination with a saddle stitcher, both the delivery mechanism A and the stitching machine portion B being supported upon a common base portion C. The stitching machine comprises a saddle 1 of general inverted-V cross-section, upon which the assembled signatures are placed by the operator of the machine adjacent the adjustable stop 2 thereon, and stitching heads 3, two in number being shown, adjacent the discharge end of the saddle. These stitching heads, mounted upon a vertical supporting member 4, are of conventional construction and need not therefore be described in detail. An electric motor 5 housed within the base portion C operates the stitching heads through suitable connections (not shown) and drives the transverse shaft 6 through a worm and worm gear assembly 7.

Associated with each stitching head 3 is a clincher bar or anvil member 8 which is reciprocated in opposi-

2

tion to movement of such heads. Actuation of the anvil members is controlled by means of vertical member 9 provided at its lower extremity with a cam 10 which is cooperable with a camming disc 11 keyed on the transverse shaft. The automatic feed mechanism of the machine is also driven by the shaft 6 through a connection to end face 12 of the camming disc of a link 13 by means of a pin 14. Connected to the other end of the link 13 is a lever 15 pivotally connected at one end to the frame of the apparatus and having a feed slide block 16 secured to its free end. It will be apparent that the link 13 will operate to reciprocate the feed block longitudinally of the saddle. The feed block 16 has attached thereto an elongated bar 17 located within and extending lengthwise of the saddle 1 to partake of the reciprocation of the feed block. This elongated bar is provided with a feed finger 18 which projects laterally through a slot in the saddle side and an ejector finger 19 spaced from the feed finger and also projecting laterally beyond the saddle. Each of these fingers has a sloping rear edge whereby it will slide by signatures resting on the saddle when withdrawn from its forward position. The fingers are spaced apart a predetermined distance such that the ejector finger 19 will be in a position to engage an assembly at the stitching station when the feed finger 18 is located adjacent the saddle stop 2. This positioning of the fingers will ordinarily occur at the limit of the reverse movement of the feed block 16, and at the limit of forward movement, the feed finger will occupy the position adjacent the stitching station while the ejector finger will be moved to a point beyond the saddle discharge end.

In the operation of the stitching machine thus far described, an assembled signature placed on the saddle 1 will be automatically moved by the feed finger 18 to the stitching station and the stitching heads and anvil members will then operate to stitch the assembly. While this assembly is being stitched, the feed member 16 and hence the fingers 18 and 19 will be withdrawn with the finger 19 sliding by the assembly at the stitching station and coming to rest in a position in engagement therewith at the same time that the feed finger slides by and is positioned to engage a second assembly placed on the saddle. Upon the next forward motion of the feed slide the ejector finger will move the now stitched assembly beyond the saddle discharge end and the finger 18 will locate the second assembly in stitching position. The feed cycle is, of course, controlled in timed relation to the operation of the stitching head through the linkage 13, 15, and in this manner the machine is capable of continuous automatic operation.

Located adjacent the discharge end of the saddle is the delivery mechanism A comprising a normally vertical transfer plate 20 which in this position is aligned with the stitching machine saddle and is adapted to have the stitched signatures placed thereon by the ejector finger 19. The plate may be provided with an adjustable stop 21 to limit such movement of the signatures, and a curved guide plate 22 may be utilized to partially compress the signature assemblies as they move onto the plate. Pivotally connected at 23 to the respective sides of the transfer plate are the arms 24 which are connected at their other ends to crank arms 25 fixedly attached to a transverse drive shaft 26. A further arm 27 is pivotally connected to one side of the plate at point 28 below the pivotal connections 23. Such further arm is also pivotally connected to the supporting frame 29 of the delivery mechanism and cooperates with the arms 24 to translate the transfer plate 20 in a manner hereinafter described.

Frame 29 projects forwardly from the stitching machine, as shown, and may be supported at its outer extremity by means of a diagonal brace 30. The frame houses and supports a generally horizontal conveyor 31 which is of the endless belt type and is provided with a drive roller 32 at its inner end and a guide roller 33 at its outer limit. The drive roller 32 is mounted on a shaft 34 supported by the frame side brackets 35, while the guide roller 33 is mounted on a shaft 36 supported by adjustable bracket members 37 likewise attached to the frame sides. A curved collecting tray 38 may be

bolted to the brackets 37 to receive the signature assemblies transported by the conveyor.

A transverse member 39 is disposed above the belt conveyor 31 intermediate the ends thereof to support a shaft 40 upon which are mounted plural friction wheels 41 in spaced apart relation. Also secured to the member 39 is a rearwardly and upwardly extending guide plate 42 adapted to guide the stitched signatures as they are moved from the transfer plate to the conveyor, and the several friction wheels 41 are located relative to the conveyor so as to frictionally engage the signature assemblies thereon. Positive drive means for the belt conveyor and friction wheels is provided in the form of a shaft 43 having a pair of pulleys 44 and 45 affixed thereto. The pulley 44 receives a belt 46 which passes over a pulley 47 mounted on the drive roller shaft 34 while the pulley 45 is operative through belt 48 and pulley 49 on shaft 40 to rotate the friction wheels. Belt 48 is reversed so that the single shaft 43 is operable to drive both the conveyor drive roller and the friction wheels in the same direction.

In order to render operation of the apparatus completely automatic, it is desirable that the delivery mechanism be operated in timed relation with the operation of the stitching machine and hence the automatic ejection of the stitched assemblies therefrom. To this end, there is provided a link 50 rotatably connected at one end to the link 13 of the stitching machine feed mechanism and at its other end to a bar 51 which is centrally pivoted on the supporting structure of the apparatus. Connected to the other end of bar 51 is a vertically extending rod 52 which constitutes the main drive element for both the transfer plate 20 and the belt conveyor with its associated friction wheels.

With particular reference to Figs. 1 and 4, the rod 52 is connected to one arm of a bell crank 53 which is rotatable upon the shaft 26. Fixedly attached to this shaft adjacent the bell crank is a collar 54 having a vertical upstanding and laterally extending portion 55 which is provided with a stud 56 adapted to engage the other arm of the bell crank. A depending ear 57 on the collar has attached thereto a spring 58 the other end of which is secured to a bracket 59 on the frame 29. Such spring is operative to bias the stud follower 56 and therefore the shaft 26 in a counter-clockwise direction as viewed in Fig. 4 into engagement with the bell crank 53. The movement in this direction is, however, limited by a stop 60 which engages the spring support 59 and the crank is thus capable of oscillation to a greater extent than the resultant oscillation of shaft 26. When arm 52 is vertically raised, the crank 53 will, through the connection described, rotate the shaft 26 and thereby cause the crank arms 25 to move in a clockwise position from the position shown in Fig. 2. This movement of such crank arms will tend to lift the transfer plate 20 through arms 24; however, the arm 27 of fixed length will influence this action in such manner that the plate will be rotated and translated in the direction of the conveyor 31. The position of the transfer plate at the limit of this motion is shown in Fig. 3, and it will be apparent that a signature assembly resting on the plate will slide off and be deposited flatwise on the belt conveyor. The vertical arm of the bell crank 53 has connected thereto a bar 62 which in turn is connected to a projection 63 on a sleeve 64 rotatable upon the conveyor drive shaft 43. At the other end of sleeve 64 is a vertical arm 65 upon which a pawl support 66 is rotatably mounted. Such support is formed with a handle 67 and adjustably receives a pawl 68 by means of the screws 69. Fixedly secured to shaft 43 is a ratchet wheel 70 disposed to be engaged and driven by the pawl 68. Oscillation of the bell crank 53 by rod 52 therefore not only actuates the transfer plate 20 but also the shaft 43 to advance the conveyor and friction wheels. By virtue of the adjustable mounting of the pawl 68, the angular displacement of shaft 43 through engagement with the ratchet wheel and the advance of these elements may be varied to accommodate pamphlets and signature assemblies of varying size.

The manner in which this delivery mechanism operates in conjunction with the stitching machine will now be described. The ejector finger 19 of such machine will automatically place an assembly after stitching on the transfer plate 20 which will receive and support the same in the vertical, partially opened condition in which

it was supported on the saddle. In this discharge operation, the guide plate 22 is utilized to avoid any interference of the signature movement by the adjacent parts of the delivery mechanism. As the feed slide 16 is moved in a reverse direction relative to the saddle 1, the rod 52 is elevated through links 50 and 51 to rotate the shaft 26 which will move the transfer plate to the position shown in Fig. 3 and thereby deposit the assembly thereon flatwise on the belt conveyor 31. At the same time the pawl 68 will ride freely over the ratchet wheel 70 in well-known fashion and hence the conveyor and friction wheels will be idle. The transfer plate will then be returned by the downward motion of the rod 52 to its normal position where it will be ready to receive the next signature assembly discharged by the stitching machine. This reverse or downward motion will cause the drive shaft 43 to be rotated through the pawl and ratchet mechanism, thereby to advance the conveyor and friction wheels and move the thus deposited signature assembly. It will be apparent that the step advance of the conveyor will result in successive signatures being deposited thereon in overlapped relation and, since the signatures are laid flatwise, the stitching may be readily inspected. The stitched signatures are moved along the conveyor to the collecting tray 38 which has a slight downward inclination effective to partially stack the assemblies.

It will be apparent from the foregoing that my improved delivery mechanism efficiently transfers the assemblies discharged by the stitching machine in such a manner that they may be readily inspected for proper stitching and conveniently gathered for further disposition. The operation of the delivery mechanism is positive and synchronously related to operation of the stitching machine to render the apparatus fully automatic thus permitting its use by a single operator. Changes in the construction specifically illustrated and described will, of course, suggest themselves to those skilled in the art, such changes, however, being within the basic idea of the invention.

Other modes of applying the principle of the invention may be employed, change being made, as regards the details described, provided the features stated in any of the following claims, or the equivalent of such, be employed.

I therefore particularly point out and distinctly claim, as my invention:

1. In a signature stitching machine having a saddle along which the signature to be stitched is moved and a synchronously operated ejector for moving the signature after it has been stitched beyond the discharge end of said saddle, a normally vertical transfer plate arranged adjacent the saddle discharge end in aligned relation therewith to receive and support the signature as discharged from the saddle, a receiver for the stitched signature likewise arranged adjacent the discharge end of the saddle, and means adapted to move said plate to cause the same to deposit the signature resting thereon flatwise upon said receiver, said means being operative in synchronism with operation of the stitching machine.

2. In a signature stitching machine having a saddle along which the signature to be stitched is moved and a synchronously operated ejector for moving the signature after it has been stitched beyond the discharge end of said saddle; a normally vertical transfer plate arranged adjacent the saddle discharge end in aligned relation therewith to receive and support the signature as discharged from the saddle, a belt conveyor likewise arranged adjacent the discharge end of said saddle, and means adapted to move said plate to cause the same to deposit the signature resting thereon flatwise upon said conveyor, said means being operative in synchronism with operation of the stitching machine.

3. In a signature stitching machine having a saddle along which the signature to be stitched is moved and a synchronously operated ejector for moving the signature after it has been stitched beyond the discharge end of said saddle; a normally vertically transfer plate arranged adjacent the saddle discharge end in aligned relation therewith to receive and support the signature as discharged from the saddle, an adjustable stop limiting signature movement on said plate, a receiver for the stitched signature likewise arranged adjacent the discharge end of the saddle, and means adapted to move said plate to cause the same to deposit the signature resting thereon

flatwise upon said receiver, said means being operative in synchronism with operation of the stitching machine.

4. In a signature stitching machine having a saddle along which the signature to be stitched is moved and a synchronously operated ejector for moving the signature after it has been stitched beyond the discharge end of said saddle; a normally vertical transfer plate arranged adjacent the saddle discharge end in aligned relation therewith to receive and support the signature as discharged from the saddle, a generally horizontal belt conveyor likewise arranged adjacent the discharge end of said saddle, and means operative simultaneously to rotate and translate said plate in the direction of said conveyor to cause the same to deposit a signature resting thereon flatwise upon said conveyor, said means being operative in synchronism with operation of the stitching machine.

5. In a signature stitching machine having a saddle along which the signature to be stitched is moved and a synchronously operated ejector for moving the signature after it has been stitched beyond the discharge end of said saddle; a normally vertical transfer plate arranged adjacent the saddle discharge end in aligned relation therewith to receive and support the signature as discharged from the saddle, a generally horizontal belt conveyor likewise arranged adjacent the discharge end of said saddle, a drive roller for said conveyor, means operative in synchronism with operation of the stitching machine simultaneously to rotate and translate said plate in the direction of said conveyor to cause the same to deposit the signature resting on the plate flatwise upon the conveyor, and drive means for said drive roller operative to rotatively advance such roller in response to operation of said means whereby said conveyor will be actuated in timed relation with movement of said transfer plate.

6. In a signature stitching machine having a saddle along which the signature to be stitched is moved and a synchronously operated ejector for moving the signature after it has been stitched beyond the discharge end of said saddle; a normally vertical transfer plate arranged adjacent the saddle discharge end in aligned relation therewith to receive and support the signature as discharged from the saddle, a generally horizontal belt conveyor likewise arranged adjacent the discharge end of said saddle, a drive roller for said conveyor, means operative in synchronism with operation of the stitching machine simultaneously to rotate and translate said plate in the direction of said conveyor to cause the same to deposit a signature resting thereon flatwise upon the conveyor, drive means for said drive roller operative to rotatably advance such roller in response to operation of said means whereby said conveyor will be actuated in timed relation with movement of said transfer plate, and adjusting means for said drive means operative to vary the responsive rotative advance of said roller and hence the movement of said conveyor in such timed relation.

7. Delivery mechanism for a signature stitching machine and the like comprising a normally vertical transfer plate adapted to support a stitched signature as discharged from the stitching machine, a belt conveyor disposed adjacent said plate, and means operative to swing said plate upwardly and laterally to deposit a signature resting thereon directly flatwise upon said conveyor.

8. Delivery mechanism for a signature stitching machine and the like comprising a normally vertical transfer plate adapted to support a stitched signature as discharged from the stitching machine, a generally horizontal belt conveyor disposed adjacent said plate, a drive for said conveyor, and means operative simultaneously to rotate and translate said plate to cause the same to deposit a signature resting thereon directly flatwise upon said conveyor, said drive being actuated in synchronism with operation of said means.

9. Delivery mechanism for a signature stitching machine and the like comprising a normally vertical transfer plate adapted to support a stitched signature as discharged from the stitching machine, a generally horizontal belt conveyor disposed adjacent said plate, a drive roller for said conveyor, means operative simultaneously to rotate and translate said plate to cause the same to deposit a signature resting thereon directly flatwise upon said conveyor, drive means for said drive roller operative to rotatively advance such roller in response to operation of said means whereby said conveyor will be actuated in timed relation with movement of said transfer plate, and adjusting means for said drive means operative to

vary the thus responsive rotative advance of said roller and hence the movement of said conveyor in such timed relation.

10. Delivery mechanism for a signature stitching machine and the like comprising a normally vertical transfer plate adapted to support a stitched signature as discharged from the stitching machine, a generally horizontal belt conveyor disposed adjacent said plate, a drive roller for said conveyor, a rotatable friction element so located above said conveyor as frictionally to engage signatures carried thereon, means operative simultaneously to rotate and translate said plate to cause the same to deposit a signature resting thereon directly flatwise upon said conveyor, and drive means for said drive roller and said friction element operative to rotatively advance the same in synchronism with operation of said means.

11. Delivery mechanism for a signature stitching machine and the like comprising a normally vertical transfer plate adapted to support a stitched signature as discharged from the stitching machine, a generally horizontal belt conveyor disposed adjacent said plate, a drive roller for said conveyor, a friction wheel so located above said conveyor as frictionally to engage signatures carried thereon, means operative simultaneously to rotate and translate said plate to cause the same to deposit a signature resting thereon directly flatwise upon said conveyor, and a collecting tray located at the discharge end of said conveyor adapted to receive stitched signatures transported thereby.

12. In a signature stitching machine having drive means and a feed member connected for reciprocation thereby; a normally vertical transfer plate adapted to receive and support the stitched signature assemblies as discharged from the machine, motion transmitting means operative to translate said plate between its normal vertical position and a substantially horizontal position in which a signature assembly thereon will slide off the same, a receiver adapted to collect in flat condition the signature assemblies thus transferred, a rock shaft for actuating said motion transmitting means, and a link connection between said rock shaft and the drive means of the machine adapted to cause said shaft to move the transfer plate in synchronism with reciprocation of the feed member, said link connection being so constructed and arranged that the plate will be translated to deposit a stitched assembly on the receiver during retraction of the feed member and will be returned to its vertical position in time to receive the next succeeding assembly discharged by the machine.

13. In a signature stitching machine having drive means and a feed member connected for reciprocation thereby; a normally vertical transfer plate adapted to receive and support the stitched signature assemblies as discharged from the machine, a crank connected to said plate operative when actuated to raise and lower the same, an arm pivotally connected at one end to said plate at a point spaced vertically from the crank connection therewith and at its other end to a stationary pivot, said arm causing the plate to tilt when raised by said crank to a substantially horizontal position in which a stitched assembly thereon will slide off the same and to return to normal vertical position when lowered, a receiver adapted to collect the stitched assemblies thus transferred by said plate, a rock shaft for rotating said crank between its operative limits, and a link connection between said rock shaft and the drive means of the machine adapted to cause said shaft to move the transfer plate in synchronism with reciprocation of the feed member, said link connection being so constructed and arranged that the plate will be translated to deposit a stitched assembly on the receiver during retraction of the feed member and will be returned to its vertical position in time to receive the next succeeding assembly discharged by the machine.

14. In a signature stitching machine having drive means and a feed member connected for reciprocation thereby; a normally vertical transfer plate adapted to receive and support the stitched signature assemblies as discharged from the machine, a crank connected to said plate operative when actuated to raise and lower the same, an arm pivotally connected at one end to said plate at a point spaced vertically from the crank connection therewith and at its other end to a stationary pivot, said arm causing the plate to tilt when raised by said crank to a substantially horizontal position in which a stitched assembly thereon will slide off the same and to return to normal

vertical position when lowered, a rock shaft for rotating said crank between its operative limits, a link connection between said rock shaft and the drive means of the machine adapted to cause said shaft to move the transfer plate in synchronism with reciprocation of the feed member, a belt conveyor adapted to receive in flat condition the stitched assemblies thus transferred by the plate, and drive means for said conveyor including a pawl and ratchet mechanism actuated by said link connection to advance the conveyor during return movement of said transfer plate.

15. Delivery mechanism for signature stitching machines and the like comprising a normally vertical transfer plate adapted to support a stitched signature assembly by engaging the inner fold thereof, a crank connected to a vertical edge of said plate operative when actuated to raise and lower the same, an arm pivotally connected at one end to the plate at a point spaced vertically from the crank connection and at its other end to a stationary pivot, thereby causing the plate to tilt when raised and lowered by the crank, a rock shaft for rotating said crank, and drive means for oscillating said shaft to move said plate between its normal vertical position and a substantially horizontal position in which a stitched assembly thereon will slide off the same.

16. Delivery mechanism for signature stitching machines and the like comprising a normally vertical transfer plate adapted to support a stitched signature assembly by engaging the inner fold thereof, a crank connected to a vertical edge of said plate operative when actuated to raise and lower the same, an arm pivotally connected at one end to the plate at a point spaced vertically from the crank connection and at its other end to a stationary pivot, thereby causing the plate to tilt when raised and

lowered by the crank, a rock shaft for rotating said crank, drive means for oscillating said shaft to move said plate between its normal vertical position and a substantially horizontal position in which a stitched assembly thereon will slide off the same, a belt conveyor adapted to receive the stitched assemblies thus transferred by the plate, and means for advancing said conveyor intermittently in timed relation with the return movement of said plate.

17. Delivery mechanism for signature stitching machines and the like comprising a normally vertical transfer plate adapted to support a stitched signature assembly by engaging the inner fold thereof, a crank connected to a vertical edge of said plate operative when actuated to raise and lower the same, an arm pivotally connected at one end to the plate at a point spaced vertically from the crank connection and at its other end to a stationary pivot, thereby causing the plate to tilt when raised and lowered by the crank, a rock shaft for rotating said crank, drive means for oscillating said shaft to move said plate between its normal vertical position and a substantially horizontal position in which a stitched assembly thereon will slide off the same, a belt conveyor adapted to receive the stitched assemblies thus transferred by the plate, and a pawl and ratchet mechanism actuated by said drive means to advance the conveyor in steps coincident with the return movement of said plate.
